AUTOMATIC COAL DUMPING APPLIANCE

Frank E. Christopher, Morgantown, W. Va.

Application August 2, 1946, Serial No. 688,060

4 Claims. (Cl. 214—123)

1

My present invention relates generally to improvements in hoist-line appliances for elevating, conveying, and dumping coal, and similar materials, and more particularly to an improved automatic coal dumping appliance of the type employing a hoist-line lift or elevator and a tiltable or invertible cage, for conveying and side-dumping a car loaded with suitable material for the purpose.

The primary object of the invention is the provision of an appliance of this type which may be erected at a desired location for receiving successive car-loads and elevating the loaded cars and dumping their fluent contents into a bin or other receptacle; and means, simple in construction and operation are provided for handling the loaded and unloaded cars with facility and dispatch.

The invention consists in certain novel combinations and arrangements of parts as will be hereinafter more fully set forth and claimed. In the accompanying drawings I have illustrated one complete example of the invention embodied in a tower-type of appliance for handling fluent material, as coal, and constructed according to one mode I have devised for the practical application of the principles of my invention. It will be understood that various changes and alterations may be made in the location of the appliance, in the material handled, and in the exemplifying mechanical structures, within the scope of my appended claims, without departing from the principles of the invention.

Figure 1 is a view in elevation of the tower type of appliance in which my invention is embodied, with the lift or elevator in lowered position; and Figure 2 is a front elevation showing the hoist-line equipment, parts being broken away for convenience of illustration;

Figure 3 is an enlarged, horizontal, transverse sectional view, as at line 3—3 of Figure 1;

Figure 4 is a vertical sectional view at the base of the tower with the lift in lowered position;

Figure 5 is a vertical sectional view showing the lift in elevated position and the cage and car at the initial movement of the dumping operation;

Figure 6 is a vertical sectional view illustrating another step in the dumping operation;

Figure 7 is a similar view with the cage and car at the end of the dumping movement in position to empty the load through the discharge chute of the cage into the delivery chute that leads to a bin or other appropriate receptacle;

Figure 8 is an enlarged detail view, as at line 8—8 of Figure 7, showing a retaining device for the cage;

Figure 9 is a fragmentary view in perspective of a portion of the guide rail for the cage retaining device.

In the assembly views Figures 1 and 2, a tower

5 or upright open frame is erected with four corner posts 1, upon the fixed base 2, and a lateral delivery chute 3 is rigidly mounted at a suitable height on one side of the tower to receive coal from the loaded car C, and deliver the contents of the car, by gravity, into a bin, or other receptacle, not shown.

10 The open upright frame provides a support for the lift or elevator in which the cage and the coal car are carried or conveyed, and the lift as shown is an open rectangular frame or structure including upper and lower horizontal bars 4, 4 and upright corner posts 5 which form guides within the interior of the tower, together with a horizontal, open-center deck-portion 6, upon which spaced rail-sections 7 are mounted. When the lift or elevator is in lowered position, these rail sections 7 are aligned with the usual railroad tracks as indicated at 8 in dotted lines in Figure 3, along which the loaded cars are run to the elevator, and the empty cars are run from the elevator.

15 In its vertical movement, the lift is guided by means of a pair of spaced upright stationary rails 9, 9 of the tower or main frame, and upper and lower pairs of guide bars 10, 10, that form grooves at opposite sides of the lift for guiding co-action with the rails and stabilizing the vertical movement of the lift.

20 These upper and lower guides of the lift are braced by diagonal bars 11, 11, and beneath the lift these braces and bars are united by a base member 12, that co-acts with a fixed bumper or stop plate 13 at the bottom of the tower 1.

25 The lift is elevated and lowered by means of a hoist-line or cable 14 which is attached at 15 to the top portion of the lift, and the hoist-line leads upwardly and over an upper supporting pulley 16, journaled near the top of the tower, and from thence the hoist-line extends to and around a hoisting drum or other operating appliance, not shown.

30 From the operating appliance or drum, the cable extends as a counterbalancing flight or line 14', upwardly and over an idler pulley 18 journaled at the top of the tower, and a counterbalancing weight 19 is suspended at the end of the counterbalancing line 14'.

35 The weight is designed to counterbalance a usual load equal to the weight of the lift, the dumping cage, the coal car C, and approximately one-half of the weight of the coal contained in the car, in order that the hoisting mechanism may be controlled with facility in raising the load, and in lowering the elevating equipment with the empty coal car.

40 The weight is guided in its vertical movement by means of perforated ears or bracket eyes 20, mounted thereon, which traverse spaced upright parallel bars or guide rods 21, 21 extending

from the base of the tower up to one of the horizontal angle iron braces 22 that surround the tower.

The loaded car C is run on the track rails 8 and short sections 7, to a pair of rail sections 23, that are mounted upon the top of a rectangular, flat floor 24 of the dumping cage which carries the car within the lift.

The cage is pivotally supported off its load center within the lift by means of a horizontal pivot bar 25 that is rigidly mounted off center below the deck or floor by means of bracket hangers 26 of the cage, and journalled to turn in complementary bearing hangers or brackets 27 of the lift.

The pivot bar 25 of the dumping cage is braced by means of spaced hoops or endless bands 28 that surround the cage, passing beneath the floor or deck and up the sides of the cage where they are united, as by welding, to horizontal angle iron bars 29, one flange of which performs the functions of a retaining bracket at one side of the car. The flange overhangs or overlaps the upper edge of the side wall of the car; within the cage, and aids in retaining the car in place while it is being swung to dumping position.

The bands 28 project above the car, and upon the spaced converging arms of the bands is mounted and rigidly supported, a discharge trough or chute 32 of sheet metal which extends the full length of the car in position to receive the coal therefrom when the car is inverted, and to pass the coal into the delivery chute 3 when the lift has been elevated to dumping position with relation to the delivery chute.

The cage, with its contained loaded car is tilted or overturned, automatically, by the lifting or hoisting movement of the hoist line 14 in connection with the counterbalancing line 14'. Formed integral with each of the straight portions of the endless bands 28 as they pass up one side of the cage are the upwardly extending outwardly inclined exterior hooks 33 which, with the endless bands 28, provide a guide slot at each end of the cage having a closed end located at the floor level of the cage, and the normally open upper end thereof flaring outwardly and terminating at a point approximating the bottom of the car body.

For automatically co-acting with the endless bands 28 and the complementary hooks 33 for dumping the car load, axially alined, horizontal stud shafts 34 are rigidly mounted upon spaced posts of the tower or upright frame, and rollers 35 are journalled on the stud shafts at the top of the delivery chute 3 and in the path of the upward movement of the bands 28 and hooks 33.

To maintain the proper vertical movement of the lift and resist tendency of the loaded tilting cage to pull the lift with it in its overturning movement, an upright guide rail 36 is provided, which is mounted within the frame, and is secured at its lower end to the base 2 of the tower, and at its upper end attached to one of the surrounding braces 22 of the tower.

For co-action with the guide rail, a roller 37 is journalled in the enlarged end 38' of a horizontally disposed slide bar 38 which is adapted to reciprocate in a bearing plate 39 bolted to a fixed support 5' of the lift. By means of a spring 40 coiled about the bar and interposed between the enlarged end 38' and the bearing plate or bracket 39, the roller is pressed into rolling contact with the inner face of the lower portion of the guide rail, and the outward longitudinal movement of

the roller may be limited by a stop pin 41 fixed upon the inner end of the bar.

In the initial upward movement, the lift is guided by the roller against the inner face of the rail; but upon approaching the elevated dumping position of the cage, the roller is automatically shifted outwardly from its spring-pressed position to engage the outer portion of the rail and positively hold the lift against movement away from the rail, thus holding the lift against partaking of the tilting movement of the cage, when the cage is overturned.

To accomplish this shifting movement of the retaining roller 37, the rail 36, just below the dumping station, of the tower, is interrupted, as at 42, to form a gap or slot for passage of the roller, to pass therethrough to engage the outer portion of the rail as shown in Figure 5.

Thus, as the lift approaches the dumping station of the tower, the roller is projected by its spring through the gap or slot 42 and the upwardly traveling roller moves in rolling contact with the outer face of the rail 36 to retain the lift against movement toward the fixed delivery chute. In the position of Figure 5, the stop pin 41 of the draw bar 38, in engagement with the slide bearing bracket or plate 39, receives and absorbs the strain that tends to sway the lift toward the delivery chute, 3.

In Figures 5, 6 and 7, the automatic operation of overturning the cage, dumping the coal car, and righting the cage with its contained unloaded car, under hoisting movement applied to the lift by the hoist-line and the succeeding lowering movement of the lift, are illustrated. As the lift is elevated, the hooks 33 with endless bands 28 slip under the pivot rollers 35 and the confined rollers in contact with the endless bands 28 and hooks 33 gradually swing the discharge chute 32 outwardly and downwardly while the pivot bar 25 ascends with the lift, thus overturning the cage and car for dumping the load into the delivery chute 3.

In dumping position, the overturned cage is supported by the endless bands 28 and hooks 33 on rollers 35 and by pivot bar 25 of the lift, and the lift is elevated by the hoist-line until the load is emptied from the discharge chute; then the movement of the hoist-line 14 is reversed to lower the lift and right the cage with its empty car. As the lift moves downwardly, the pivot bar 25 swings the cage, causing the endless bands 28 to ride downwardly and outwardly on the pivot rollers 35, and as the cage is upturned or righted, the tracks 55 swing upwardly on the rollers 35, and the hooks 33 co-act with the rollers to stabilize the position of the upturned cage.

Having thus fully described my invention, what I claim as new and desire to secure by Letters Patent is:

1. In a hoist-line appliance, the combination with an upright frame having an off-set guide rail, a vertically movable lift suspended in the frame, a cage pivotally mounted in the lift, and co-acting means on the cage and frame for overturning the cage, of a resiliently supported roller mounted on the lift in rolling contact with the inner side of said rail and adapted to pass through said gap for engagement with the outer side of said rail, and means for limiting the longitudinal movement of the roller mount.

2. A hoist-line appliance comprising an upright frame having an offset guide rail, a vertically movable lift suspended in the frame, a cage pivotally mounted on the lift, coacting means

on the cage and frame for overturning the cage, a bracket guide secured to the lift at the side thereof opposite from which the cage is overturned, a slide bar adjustable in said bracket, a roller journalled on the slide bar and normally engaging with the inner side of said offset guide rail, a spring on the bar reacting against the bracket guide and urging the roller into contact with the rail, said rail having a gap to permit the passage of the roller to the outer side of the guide rail to retain the lift while the cage is being pivoted and a stop in on the bar and engageable with the bracket to limit the outward movement of the bar.

3. A hoist-line appliance comprising an upright frame having an offset guide rail, a vertically movable lift suspended in the frame, a cage pivotally mounted on the lift and adapted to receive and retain a car loaded with material, hook means extending from the side of the cage, 15 projections on the frame adapted to be engaged by the hook means to overturn the cage with the car, and means cooperating between the offset guide rail and the lift and adapted to be extended from one side of the guide rail to the opposite 20 side automatically as the lift is raised to be overturned whereby to retain the opposite side of the

lift from which the carriage is overturned against the overturning of the lift.

4. A hoist-line appliance comprising an upright frame having an offset guide rail, a vertically movable lift suspended in the frame, a cage pivotally mounted on the lift, coating means on the cage and frame for overturning the cage, and means cooperating between the offset guide rail and the lift and adapted to be extended from 10 one side of the guide rail to the opposite side automatically as the lift is raised to be overturned whereby to retain the opposite side of the lift from which the carriage is overturned against the overturning of the lift.
